RAILWAY CAR TRUCK

John J. Tatum, Baltimore, Md.

Application November 4, 1930. Serial No. 493,426

10 Claims. (Cl. 105—218)

This invention relates to the trucks of railway cars, particularly passenger cars.

Passenger car trucks, as now commonly constructed, are provided with positively guided journal boxes, each journal box being mounted in a pedestal so as to be guided in position and in its movements by flanges on its sides engaging the pedestal legs, as a result of which the journal box is not free to adjust itself to irregularities in the position of the pedestal and to irregularities in the journal at the same time; as, for instance, if the pedestal flares outwardly or inwardly from a plumb or vertical line the box is required by the guides bearing on the legs of the pedestal to position itself on the journal whichever way the pedestal happens to be attached to the truck. This often throws the load carried by the truck on the back end of the journal bearing in the box, or on the front end, resulting in a small bearing area of the journal bearing being overloaded to such an extent that binding between the journal bearing and the journal occurs and oil is prevented from flowing between the bearing and journal for the lubrication of the bearing surfaces. Accordingly, what is known as a hot journal occurs, whereby the journal is damaged or burnt off. Furthermore, the guides on the sides of the journal box rub hard against the pedestal legs and prevent free movement of the box between the pedestal legs brought about by the action of the cushioning springs, resulting in hard or rough riding cars. In passenger cars of usual construction, the brake beams are mounted upon hangers carried by the truck frame, which mode of mounting does not allow adjustment of the brake shoes to accommodate themselves to changes of position of the wheels, and the hanger suspension often interferes with a proper release of the brake shoe. Hence there is an objectionable amount of wheel flange and track friction and resistance to travel caused because of the inability, due to such friction and resistance, of the brake shoes to adjust themselves to the movements of the wheels in such manner as to relieve such friction and resistance. Also in passenger cars of usual construction the center bearing plates of the wheel trucks often come together, when the car is heavily loaded, causing soft surfaces of the metal center plates to freeze or adhere together, thus preventing free swinging of the truck on curves and frequently causing derailments, as well as hard grinding of the wheel flanges against the railroad track, quickly wearing both track and flange to destructive limits and making them unsafe for use

and requiring their removal and replacement at very great expense.

The primary object of my invention is to provide a floating journal box, which is free to move in the pedestal within safe limits without restriction, thus allowing the box to automatically adjust itself to prevent binding of the box or journal and the deleterious actions resulting therefrom.

A further object of my invention is to provide means which, while allowing the journal box and truck side frame in which it is mounted to have relative floating movements, will prevent relative displacement of these parts.

With these and other objects in view, the invention consists of the features of construction, combination and arrangement of parts, herein-after fully described and claimed, reference being had to the accompanying drawings, in which:

Fig. 1 is a side elevation, partly in section, of a portion of a truck frame and a journal box structure embodying my invention.

Fig. 2 is a sectional plan view of parts shown in Fig. 1.

Fig. 3 is a vertical longitudinal section through the journal box shown in Figs. 1 and 2.

Fig. 4 is a view similar to Fig. 2, showing a modified form of journal box structure.

Fig. 5 is a section similar to Fig. 3 of the journal box shown in Fig. 4.

Figs. 6, 7 and 8 are cross-sections taken respectively on the lines 6—6, 7—7 and 8—8 of Fig. 1.

Fig. 9 is a top plan view of a portion of a bottom of a car body, showing in dotted lines a part of a center bearing for a truck frame and means for lubricating the same.

Fig. 10 is a sectional view through the car bottom and a part of the center bearing of the truck, taken along the line of the lubricant feed pipe, and showing more clearly the lubricating means.

Fig. 11 is a section on an enlarged scale through the center bearing plates.

Fig. 12 is a section on the line 12—12 of Fig. 11.

In the illustrated embodiment of my invention, 1 is a side frame member of the truck frame of a railway passenger car, provided with the pedestal 2 having the jaws or legs 3 which may be provided on their inner faces with wear plates 4.

In the pedestal 2 between the legs 3 is arranged a floating journal box 5. This journal box is devoid of the usual guide flanges or other guiding connections at its sides with the pedestal legs, being of a width somewhat less than the

distance between the wear plates 4 of the legs and fitted to slide with freedom between the legs, so that it may accommodate itself to irregularities in the position of the pedestal and to irregularities in the journal at one and the same time. If, therefore, the pedestal deviates either inwardly or outwardly from a plumb or vertical line, or is warped or twisted, this condition of the pedestal will not affect the movements of the journal box, which may position itself either vertically or inwardly or outwardly with relation to the pedestal and on the journal as may be required, dependent upon the position the pedestal may happen to have upon the truck. By mounting the journal box so that it is free from guiding engagement with the pedestal, the journal box is prevented from being forcibly shifted to throw the load carried by the truck either on the back end of the journal bearing or on the front end of the journal bearing, and constricting or preventing the flow of oil between the journal bearing and the journal with the result of causing what is known as a hot journal resulting in the damaging or burning off of the journal. Furthermore, by doing away with the use of positive guiding connections between the journal box and pedestal, which rub hard against the pedestal legs and prevent free movement of the box between the pedestal legs incident to the action of the cushioning springs, wear and tear upon the journal box and pedestal and hard or rough riding of the car and other binding and constricting actions are effectually obviated. As a result, an easy riding truck or car is obtained, wear and tear and frequent replacement and repairs reduced, and the journal box allowed to have free and unimpeded movements for easy riding actions regardless of any irregularities in the form or condition of the pedestal or of the journal being slightly tapered or otherwise irregular.

The sides of the journal box may be provided with wear plates 6 to reduce wear and tear thereon and to provide easy contact between the journal box and the wear plates 6 and, if desired, a stop flange 6^a may be provided on each side of the box at the rear for engagement with the pedestal to limit the outward movement of the box.

The journal box 5 may be of the type shown in Figs. 2 and 3 in which the box is provided at its top with a fixed or integral wedge seat 7 for the journal bearing 8, disposed between the same and the journal 9, with which seat or wedge and the journal it may have an interlocking connection to assist in holding the box from inward or outward displacement on the journal and relative to the pedestal and journal. The box is provided externally at its top with side flanges 10 and front and rear flanges 11, arranged in parallel pairs and to form a pocket or socket for interlocking connection with a depending or depressed part of the end 12 of the equalizer bearer 13. This end of the bearer seats on a rib 13' along the top of the bearing block 15 between the flanges 11, thereby forming an interlock between the journal box and the bearer, which allows the journal box to have free and easy upward and downward floating movements, while preventing either inward or outward displacement of the journal box. Thus by the use of this interlocking connection between the equalizer bearer, sustaining the pressure of the cushioning springs 14, and the journal box and the interlocking connection between the journal bearing 8 and the seat of wedge 7 and the journal

9, the journal box is held from displacement while permitted to have automatic adjusting and floating movements, thus securing a highly efficient cushioning action for easy riding and adjustment of the journal boxes with the journals, without binding restriction, to permit the wheels to accommodate themselves to curves and irregularities in the track rails, and frictional wear and tear is reduced to the minimum, giving longer life to the journal boxes and pedestals and obviating the expensive frequent repairs and replacements now necessary incidental to the use of pedestals and journal box mountings of ordinary construction. The pocket or socket formed by the flanges 10 and 11 may also serve to receive a cushioning damper of rubber or other elastic material engaged by the end of the bearer 13 and forwarding a cushioning action for the movement of the bearer, while preventing objectional grinding noise and wear and tear due to direct contact of metal upon metal.

The journal box construction disclosed in Figs. 2 and 3 adapts the seat or wedge for the journal bearing to be cast with the roof of the box, thereby eliminating what is commonly known as the journal bearing key, commonly made use of to hold the journal bearing in place and which, as ordinarily constructed, is provided with a radial top to allow adjustment for the journal bearing on the journal, which becomes inoperative because of the wear on the back of the wedge and inside of the top of the journal box and also because of the radius on top of the journal box wedge wearing flat. My construction of the journal box avoids the extra cost of the wedge and eliminates entirely the wear and tear on top and on the inside of the roof of the box when the wedge is used as a separate piece.

I may, however, employ the construction of journal box shown in Figs. 4 and 5, in which the integral wedge 7 is removed and a standard type of A. R. A. wedge 7^a used in its place, which wedge interlocks in a suitable manner with the box and has an interlocking connection with the journal bearing 8, which in turn has an interlocking connection with the journal 9. While the construction of journal box shown in Figs. 2 and 3 is simpler and less expensive, that shown in Figs. 4 and 5 may be used with equal working efficiency.

The described construction of truck design including the floating journal box, arranged and mounted as set forth, does away with the use of a multiplicity of parts, equal in number to about two hundred pieces per car, avoiding the purchase cost of such items, the inspection requirements, and the maintenance cost, and producing a truck containing less parts subject to damage or breakage and giving easier and quieter riding of the trucks under the car, and doing away largely also with the hazards incident to the use of trucks of ordinary construction containing so many parts liable to cause derailments and other accidents.

In accordance with my invention, I also mount the brake heads 16 on the brake beams 17, each mounted at its upper end on a pivot bolt or member 18 engaging inclined slots 19 in the fork plates 20 of forked hangers carried by the truck frame, and on which bolt the brake head 145 may slide laterally whereby the brake beams and shoes are mounted to slide toward and from the wheels in a path inclined to the horizontal, as well as to have pivotal movements to adapt the brake shoes to adjust themselves to the wheels

in a braking action. The arrangement is such construction, mode of operation and advantages that after application, and upon release of the brake mechanism, the brakes will automatically by their weight or by the action of gravity move 5 away from the wheels due to the outward and downward inclination of the slots 19. By this means the brake heads are mounted for free and easy automatic adjustments to suit varying conditions of the brake rigging and wheels in the 10 brake applying and releasing actions, and to recede positively on a brake releasing action so as to prevent the undue wear and tear caused ordinarily by continuance of engagement of the 15 brake shoes with the wheels after a brake releasing action. This construction also obviates the use of the ordinary brake hangers, pins and keys and the well known objections incident thereto. In addition the mounting of the brake 20 shoes to slide laterally adapts the same to so move under pressure of the wheel flanges thereon as the wheels adjust themselves to curves and variations in the rails, thus preventing the brake heads from resisting such movements of the 25 wheels and causing track and flange resistance to travel and undue wear and tear upon such parts.

As shown particularly in Figs. 9, 10 and 11, the truck is provided with a center bearing plate 21 for coaction with a center bearing plate 22 on the car, and said plate 21 is formed with an upstanding central circular bearing stud 23 and an annular channel 24 surrounding the same, while the plate 22 is provided with a depending annular bearing member or ring 25 which surrounds the stud 23 and enters the annular channel 24, whereby the truck is mounted to swing upon the car. In order to prevent direct contact between the opposed surfaces of the channel 24 and ring 25 an annular hard metal wear plate 26 40 is disposed between said surfaces in the channel. This ring plate acts as an effective distributor of introduced lubricant, and serves to better sustain the wear and to prevent direct contact between the soft metal surfaces of the center plates which 45 are subject to friction and heating and are liable to bind or freeze under certain conditions. The hard metal wear plate 26 prevents any binding or freezing due to such causes, so as to obviate accidents due to ruptures or derailments when 50 the truck is bound and prevented from having a free swinging action. The bottom wall of the channel 24 and bottom surfaces of the ring 25 are provided with annular and radial lubricant distributing grooves 27 and 28 which intersect 55 vertical lubricant supply channels 29 in the plate, the channel in the plate 22 being connected with a lubricant feed pipe 30 supported by brackets 31 on the top plate and car body and provided at its free end with a reducer 32 and a suitable fitting 60 33 for application of a lubricant pressure pump whereby lubricant under proper pressure may be supplied from a side or from one end of the car to the center bearing to keep the parts thereof properly lubricated, without the necessity of lifting the car off the truck, or the operator getting 65 under the car to supply the lubricant. By the provision of a center bearing with a wear plate between the centering plates and a lubricant feed means of the character described, trucks 70 may be kept well lubricated in a ready and easy manner and prevented from freezing, so as to entirely eliminate all liability of binding and freezing of the trucks.

From the foregoing description, taken in connection with the accompanying drawings, the

construction, mode of operation and advantages of my invention will be readily understood without a further and extended description, and such construction and advantages appreciated by those versed in the art. While the structure disclosed 80 is preferred, it will, of course, be understood that changes in the form, construction and arrangement and proportion of parts may be made, within the scope of the appended claims, without departing from the spirit or sacrificing any of the 85 advantages of the invention.

Having thus fully described my invention, I claim:—

1. In a journal bearing for railway cars, a car truck having a pedestal, a journal box movable in the pedestal and having its sides in spaced relation to and free from guiding engagement with the legs of the pedestal so as to adapt the box to have a floating movement between said legs, and a member carried by the truck and vertically 90 movable with the box, said member having an interlocking engagement with the top of the box to hold the box from inward or outward displacement.

2. In a journal bearing for railway cars, a car 100 truck having a pedestal, a journal box movable in the pedestal and having its sides in spaced relation to and free from guiding engagement with the legs of the pedestal so as to adapt the box to have a floating movement between said legs, and 105 an equalizer bearer having an interlocking connection with the top of the box to hold the box from inward or outward displacement.

3. In a journal bearing for railway car trucks, a truck frame having a pedestal, a journal box 110 movable between the legs of the pedestal, said box having its sides spaced from and free from guiding engagement with said legs, and a spring-pressed bearer member carried by the truck and having an end portion overhanging the box and 115 having an interlocking engagement with the top thereof for holding the box from inward or outward displacement.

4. In a journal bearing for railway cars, a truck frame provided with a pedestal, a journal box 120 movable between the legs of the pedestal, said box having its sides spaced from and free from guiding engagement with the sides of the pedestal, and said box having in its top a seat socket, and an equalizer bearer having an end portion 125 engaging in said socket and interlocking with the box to hold the same from inward or outward displacement.

5. In a journal bearing for railway cars, a car truck having a pedestal, a journal box movable 130 between the legs of the pedestal and having its sides spaced from and free from guiding connections with said legs, said box being provided in its top with a locking element, and an equalizer bearer carried by the truck and having an end 135 portion provided with a coacting locking element engaging the locking element of the box to hold said box from inward or outward displacement on the journal.

6. In a journal bearing for railway cars, a truck 140 frame having a pedestal, a journal box movable between the legs of the pedestal and having its sides spaced from and free from positive guiding engagement therewith, said box being provided at its top with pairs of longitudinal and transverse walls forming a socket, the longitudinal walls being provided with notches, and an equalizer bearer having an end portion resting in said notches and interlocking with said socket to hold 145 150

the box from inward or outward displacement on the journal.

7. In a journal bearing for railway cars, a truck frame provided with a pedestal, a journal box 5 movable in the pedestal and having its sides spaced from and free from positive guiding engagement with the pedestal legs, said box being provided at its top with an internal integral wedge for the journal bearing and an external locking

10 socket, and an equalizer bearer having an end portion engaging said socket to hold the box against inward or outward displacement on the journal.

8. In a car truck, the combination with a car axle journal and a truck side plate having a 15 pedestal, of an axle box receiving the journal and operatively disconnected from and mounted for floating movement independent of and between the pedestal legs, said box and legs having their opposed surfaces constructed and arranged for 20 relatively unobstructed freedom of motion to permit the box to position itself upon the journal and to permit the box and pedestal each to have independent or conjoint vertical and lateral movements.

In a journal bearing for railway cars, a car truck having a pedestal, a journal box movable in the pedestal and having its sides in spaced relation to and free from guiding engagement with the legs of the pedestal so as to adapt the box to have a floating movement between said legs, and an equalizer bearer engaging the box to hold the box from inward or outward displacement.

10. In a journal bearing for railway car trucks, a truck frame having a pedestal, a journal box loosely mounted in the pedestal in normally spaced relation to the pedestal legs, without restricted guiding connections therebetween, so as to have free independent or conjoint vertical and lateral movements between and with respect to each other and the box to adjust itself to positions of the journal without regard to the pedestal, and an equalizer bearer engaging the box to hold the box from inward or outward displacement.
